UNITED STATES PATENT OFFICE.

JOSEPH H. STALEY, OF COLUMBUS, INDIANA.

ARBOR PRESS.

1,421,738.

Specification of Letters Patent. Patented July 4, 1922.

Application filed March 1, 1921. Serial No. 443,877.

To all whom it may concern:

Be it known that I, JOSEPH H. STALEY, a citizen of the United States, residing at Columbus, in the county of Bartholomew and 5 State of Indiana, have invented new and useful Improvements in Arbor Presses, of which the following is a specification.

This invention relates to improvements in arbor presses for placing and loosening bushings in various mechanisms, for tightening parts on arbors preparatory to the doing of lathe-work on them, and for various uses in machine construction and repair wherein a regulated pressure is needed.

15 The object of the invention is to provide a machine that can be quickly set to the particular job in hand and which will then be capable of exerting a plurality of different pressures to the development of which the 20 mechanism may be easily and quickly changed.

I accomplish the above and other objects which will hereinafter appear, by the mechanism illustrated in the accompanying drawings in which like characters of reference indicate like parts and wherein:

Fig. 1 is a view in front elevation of my invention, Fig. 2 is a view in side elevation of the machine shown in Fig. 1. Fig. 3 is 30 a detail on a larger scale of the mechanism at the top of the machine as shown in Fig. 2 for determining the ram pressure. Fig. 4 is a horizontal section of the mechanism of Fig. 3 through the ram driving shafts. Fig. 35 5 is an edge and Fig. 6 a top plan view of the table plate.

The frame of the press has an expanded base 7, column 8 terminating with a forwardly extended portion at its upper end to 40 support a ram 9 with sufficient clearance in front of the standard to avoid interference with the work, and a standard 10 on the base in front of the column, all of which parts are preferably in one-piece of cast iron 45 of heavy and strong proportions as shown. The front of the column has a planed surface 11 as a bearing for a table 12, with a pair of vertical slots 13, for the passage of bolts by which the table is slidably held 50 against said planed surface. The standard is recessed vertically to receive a screw 14, upon the upper end of which the table bears,

and within the standard is a nut 15 through which the screw operates. A bevel gear wheel 16 on the screw meshes with a similar 55 wheel 17 on a shaft journaled in the depending guide extension of the table, and on the outer end of this shaft is the hand crank 18, whereby it will be evident that by turning the crank the table will be raised 60 or lowered accordingly. The table is slotted in centrally from the front in the path of the ram to accommodate projecting portions of articles to be operated on, and to facilitate operations a table-plate 19, is provided 65 which has a series of radial slots of different widths that may be brought selectively over the slot in the table to fit the particular work in hand. The plate 19 has a pin 20 which enters a hole in the table and about which 70 pin the table is rotated. A ring 21 is clamped to the top of the standard to further hold the position of such articles as are long enough to reach that far and are passed through it, and the base is recessed at 22^a in 75 alinement with the openings above.

The ram 9 is slidingly mounted in a vertical channel in the forwardly extended portion of the column 8, where it is retained by a plate 22, and by engagement of stub gear 80 teeth 9^a on the ram with corresponding stub gear teeth 9^b cut in a shaft 23 journaled in the frame head of the press. Mounted on this shaft is a hand-wheel 24 by which the shaft may be rotated for a minimum pressure, but more generally for the purpose of 85 raising or lowering the ram in receiving and discharging the article to be pressed or that has been pressed.

Mounted in a fixed manner on the other 90 end of shaft 23 from hand-wheel 24, is a ratchet-wheel 25, and further in on the shaft but adjacent the ratchet-wheel, a hand lever hub 26 is loosely mounted on the shaft. This has a socket in which a lever 26^a is retained. 95 An extension 27 from the hub supports a counterweight 28. On the opposite side of shaft 23 from the counterweight a shaft 29 is journaled in the hub with a rocking and a longitudinal adjustment. Near its middle the shaft 29 has two suitably spaced-apart circumferential grooves 30 and 31 and above it in the hub 100 of the lever is a boss 34^a having a bore radi-

ally of the shaft 29, in which is a ball 33, pressed by a spring 34 toward the shaft, and which enters whichever one of the grooves is then in register with said bore. 5 A screw-plug 35 in the outer threaded end of the bore provides means for adjusting the compression of spring 34.

10 Mounted in a fixed manner on the outer portion of shaft 29 is a pawl 36, adapted to engage the teeth of ratchet wheel 25, when shaft 29 is in position with ball 33 in groove 30.

15 Mounted loosely on shaft 23, between the hub of lever 26^a and the frame of the press, is a ratchet wheel 37, and attached in a fixed manner to the ratchet wheel is a spur-gear pinion 38. Mounted in the head of the frame of the press is a shaft 39, on which is a fixed spur-gear wheel 40, larger than pinion 20 38, and in driving engagement therewith. Also mounted in a fixed manner on shaft 39, on the other side of the frame, is a pinion 41 which drivingly engages a spur-gear wheel 42, fixed on the shaft 23.

25 Mounted in a fixed manner on the inner end of shaft 29, is a pawl 51, which is adapted to engage the teeth of ratchet-wheel 37, when the shaft is in position with ball 33 in the groove 31. Seated in the hub of this 30 pawl is a pin with an eye to which a spring 43 is fastened and the other end of the spring is attached to a pin 44 on the lever socket. The tension of spring 43 rocks the shaft 29 in a direction to bring the pawls 35 thereon into engagement the particular ratchet wheel that is then in the plane of movement of one of the ratchets when the hand lever is lowered. The throw of rock shaft 29 is limited in opposition to the spring 40 43 by the contact of an arm 45 from the hub of pawl 51, with the end of a bolt 46 passing through a shaft 47, supported in any suitable manner. The bolt is adjustable to regulate the upward movement of arm 45 without 45 the necessity for careful machining of said parts. The shaft 47 also acts as a stop for a lug 50 on the lever hub which limits the upward movement of the hand lever under the action of the weight 28.

50 The pawls, as shown best in Fig. 3, have removable contacting plates *c* of tempered steel to take the wear, and which are removable for sharpening and replacement. They fit in a suitable notch in a cast hub 55 and are retained by a dowel pin *d* and bolt *b*.

The operation of my invention is as follows: The table 12 is adjusted to the desired height to suit the particular work to be done, by turning the hand crank 18, whereby 60 the ram 9 is correspondingly adjusted by the hand wheel 24. Shaft 23 is easily rotated by the hand wheel to raise or lower the ram when the lever 26^a is up as shown in the drawings, because both of the pawls are then disengaged. If such a ram pressure as can

be produced by rotating the hand wheel will suffice, that means alone may be used, but if a greater pressure is required the shaft 29 is pushed in until the pawl 36 is over ratchet wheel 25. In that adjustment of shaft 29 70 the ball 33 will be in groove 30, which will hold the shaft under normal conditions of use. The pawl 51 will then be so far to one side of ratchet wheel 37 that it will miss it when operated by the hand lever 26^a. Then 75 hand lever 26^a is manually lowered and its power applied through pawl 36 to shaft 23 through ratchet wheel 25.

When a still greater pressure is desired the shaft 29 is moved longitudinally to the 80 position shown in the drawings, which removes pawl 36 from position to influence ratchet wheel 25, but brings pawl 51 into action with ratchet wheel 37 when the lever 26^a is lowered. Then the power applied to 85 wheel 37 is transmitted through the multiplying gears 38, 40, to shaft 39 and thence through multiplying gears 41 and 42 to shaft 23.

While I have described my invention with 90 more or less minuteness of detail, I do not desire to be confined to the specific mechanism shown, unduly, or any more than is required by the appended claims.

I claim:

1. In an arbor press, a frame having a forwardly overhanging head, a vertically reciprocating ram in said head, said ram having gear teeth, a vertically adjustable table under the ram, a shaft mounted in the head 100 having gear teeth engaging with those of the ram, a hand lever, a spur gear wheel rotatable independently of the shaft, a second spur gear wheel mounted on the shaft in a fixed manner, selecting means for transmitting power from the lever to said first gear wheel and power multiplying means for transmitting power from the first gear wheel to the second one. 105

2. In an arbor press, a frame having a forwardly overhanging head, a vertically reciprocating ram in said head, said ram having gear teeth, a vertically adjustable table supported under the ram by the frame, a shaft mounted in the head having gear teeth engaging with those of the ram, a hand wheel on one end of the shaft, a hand lever pivoted on the shaft, a spur gear wheel loosely mounted on the shaft, a second spur gear wheel mounted on the shaft in a fixed 115 manner, selective means for transmitting power from the lever to said first gear wheel and power multiplying means for transmitting power from the first gear wheel to the second one. 120

3. In an arbor press, a frame having a forwardly overhanging head, a vertically reciprocating ram in said head, said ram having gear teeth, a vertically adjustable table supported under the ram by the frame, 125 130

a shaft mounted in the head having gear teeth engaging with those of the ram, a hand lever pivoted on the shaft, a ratchet wheel fixed on the shaft, a second ratchet wheel 5 loosely mounted on the shaft, a spur gear wheel secured to and rotating with the second ratchet wheel, pawl means for transmitting power selectively from the lever to either of said ratchet wheels, and power 10 multiplying means for transmitting power to the shaft from the spur gear wheel secured to the second ratchet wheel.

4. In an arbor press, a frame having a forwardly overhanging head, a vertically reciprocating ram in said head said ram having gear teeth, a vertically adjustable table under the ram, a shaft mounted in the head having gear teeth engaging with those of the ram, a hand lever, a spur gear wheel 20 rotatable independently of the shaft, a second spur gear wheel mounted on the shaft in a fixed manner, means for transmitting power from the lever to said first gear wheel, power multiplying means for transmitting 25 power from the first gear wheel to the second one, and means for transmitting power from the lever to the shaft independently of said power multiplying means.

5. In an arbor press, a frame having a forwardly overhanging head, a vertically reciprocating ram in said head, said ram having gear teeth, a vertically adjustable table supported under the ram by the frame, a shaft mounted in the head having gear teeth 35 engaging with those of the ram, a hand wheel on one end of the shaft, a hand lever pivoted on the shaft, a spur gear wheel loosely mounted on the shaft, a second spur gear wheel mounted on the shaft in a fixed 40 manner, means for transmitting power from the lever to said first gear wheel, power multiplying means for transmitting power from the first gear wheel to the second one, and means for transmitting power from the lever 45 to the shaft independently of said power multiplying means.

6. In an arbor press, a frame having a forwardly overhanging head, a vertically reciprocating ram supported by said head 50 said ram having gear teeth, a vertically adjustable table under the ram, a shaft mounted in the head having gear teeth engaging with those of the ram, a hand lever, a spur gear wheel rotatable independently of the shaft, a second spur gear wheel mounted on the shaft in a fixed manner, means for transmitting power from the lever to said first gear wheel, power multiplying means for transmitting power from the first gear wheel 55 to the second one comprising a second shaft, a fixed gear wheel thereon larger than and driven from the first gear wheel and a second gear wheel fixed on the second shaft smaller than and drivingly engaging the 60 gear wheel fixed on the first shaft, and

means for transmitting power from the lever to the shaft independently of said power multiplying means.

7. In an arbor press, a frame having a forwardly overhanging head, a vertically reciprocating ram mounted in said head said ram having gear teeth, a vertically adjustable table supported under the ram by the frame, a shaft mounted in the head having gear teeth engaging with those of the ram, 70 a hand lever pivoted on the shaft, a ratchet wheel fixed on the shaft, a second ratchet wheel loosely mounted on the shaft, a spur gear wheel secured to and rotating with the second ratchet wheel, pawl means for transmitting power selectively from the lever to either of said ratchet wheels, and power multiplying means for transmitting power to the shaft from the spur gear wheel secured to the second ratchet wheel comprising 75 a second shaft, a fixed gear wheel thereon larger than and driven from the first gear wheel and a second gear wheel fixed on the second shaft smaller than and drivingly engaging the gear wheel fixed on the first 80 shaft.

8. In an arbor press, a frame, a vertically reciprocating ram supported by the frame, a pivoted lever, a plurality of means for reciprocating the ram from the lever at different powers, and means for actuating a selective one of said plurality of means.

9. In an arbor press, a frame, a vertically reciprocating ram supported by the frame, a pivoted lever, a plurality of means 95 for reciprocating the ram from the lever at different powers each comprising a ratchet wheel, and pawl means on the lever adjustable to engage a selective one of said ratchet wheels one at a time.

10. In an arbor press, a frame, a vertically reciprocating ram supported by the frame, a pivoted lever, a plurality of means for reciprocating the ram from the lever at different powers each comprising a ratchet wheel, 100 a longitudinally adjustable shaft mounted on the lever, and pawl means carried by the shaft to singly engage a selective one of said ratchet wheels.

11. In an arbor press, a frame, a vertically reciprocating ram supported by the frame, a pivoted lever, a plurality of means for reciprocating the ram from the lever at different powers each comprising a ratchet wheel, 115 a longitudinally adjustable shaft mounted in the lever, resilient stop means to hold a given adjustment of the shaft, and pawl means carried by the shaft to singly engage a selective one of said ratchet wheels.

12. In an arbor press, a frame, a vertically reciprocating ram supported by the frame, a pivoted lever, a plurality of means for reciprocating the ram from the lever at different powers each comprising a ratchet wheel, a 125 shaft mounted on the lever, pawl means car-

- ried by the shaft to engage a selective one of said ratchet wheels, a stop remote from the pawl and lever, an extension from the pawl to contact the stop and rock the shaft to disengage the pawl from its ratchet wheel, and resilient means to return the shaft to position of engagement of its pawl with a ratchet wheel when the lever is moved to release the extension from the stop.
- 10 13. In an arbor press, a frame, a vertically reciprocating ram supported by the frame, a pivoted lever, a plurality of means for reciprocating the ram from the lever at different powers each comprising a ratchet wheel, 15 a shaft mounted on the lever, pawl means carried by the shaft to engage a selective one of said ratchet wheels, a stop remote from the pawl and lever, an extension from the pawl to contact the stop and rock the shaft to disengage the pawl from its ratchet wheel, said stop being adjustable toward and from the pawl extension, and resilient means to return the shaft to position of engagement of its pawl with a ratchet wheel when the 20 lever is moved to release the extension from the stop.
14. In an arbor press, a frame, a reciprocating ram supported by the frame, a pivoted lever, a power multiplying gear means

drivingly connected with the ram, and selective means for transmitting power from the lever to said gear means.

15. In an arbor press, a frame, a reciprocating ram supported by the frame and having gear teeth, power multiplying gear means engaging with the teeth of the ram, a lever, and selective means for transmitting power from the lever to said power multiplying gear means.

16. In an arbor press, a frame, a reciprocating ram supported by the frame, a lever, gear means for actuating the ram at different powers, and selective means for transmitting power from the lever to one of said ram-actuating means.

17. In an arbor press, a frame, a reciprocating ram supported by the frame and having gear teeth, a lever, a shaft having gear teeth engaging with those of the ram, power multiplying gear means drivingly connected with the shaft, and selective means for drivingly connecting the lever independently of said power multiplying gear means or through said power multiplying gear means.

Signed at Columbus, Indiana, this the 21 day of February, 1921.

JOSEPH H. STALEY,
